(57) **CLAIM**

The ornamental design for a driving device for delivery robot, as shown and described.

DESCRIPTION

1. Driving device for delivery robot

1.1 : Top, front and right-side perspective view

1.2 : Bottom, front and right-side perspective view

1.3 : Top, rear and right-side perspective view

1.4 : Front

1.5 : Back

1.6 : Left

1.7 : Top

1.8 : Bottom

1.9 : Top, front and right-side perspective view of the driving device for delivery robot in a configuration of use

This article is used to operate a delivery robot; a right view is omitted because it is a mirror image of the left view; reproduction 1.9 shows a state in use of the claimed design and portions shown in broken lines are not part of the
